UNITED STATES PATENT OFFICE.

WALLACE I. STIMPSON, OF MILFORD, MASSACHUSETTS, ASSIGNOR TO DRAPER COMPANY, OF PORTLAND, MAINE, A CORPORATION OF MAINE.

AUTOMATIC SHUTTLE-CHANGING LOOM WITH SLIDING FRONT PLATE FOR THE SHUTTLE-BOXES.

No. 853,839.

Specification of Letters Patent.

Patented May 14, 1907.

Application filed March 8, 1906, Serial No. 304,868.

To all whom it may concern:

Be it known that I, WALLACE I. STIMPSON, of Milford, in the county of Worcester and State of Massachusetts, have invented certain new and useful Improvements in Automatic Shuttle-Changing Looms with Sliding Front Plates for the Shuttle-Boxes, of which the following is a specification.

In automatic weft replenishing looms wherein the weft replenishment is accomplished by discharging the spent shuttle and inserting a fresh shuttle, it is a customary plan to move the front-plate of the shuttle-box at the supply side of the loom upwardly so as to permit the insertion of the fresh shuttle by a substantially horizontal movement into the then open shuttle-box; and, after the fresh shuttle has thus been put into place, the front-plate descends into normal position, thus closing the shuttle-box, and the fresh shuttle is then in position to proceed with the weaving operations. In such looms the fresh shuttle may not be inserted accurately into place on the race-plate of the lay and this defective position of the shuttle is enhanced in case the usual rear binder is being pressed forwardly by its usual spring at the time the fresh shuttle is inserted.

The object of the present invention is to enable the front-plate of the shuttle-box to properly descend into place in case the fresh shuttle is not accurately located on the race-plate of the lay and at the same time to force the shuttle into its proper position ready to be picked through the shed.

In carrying out the object of this invention, the front-plate of the shuttle-box at the supply side of the loom moves up and down at substantially right angles to the race-plate of the lay. The lower edge of the front-plate is made of unusual thickness and it is beveled on its inner face. The forward upper edge of the lay is recessed to receive the beveled lower edge of the front-plate. Accordingly, should the freshly inserted shuttle be misplaced on the race-plate, it will be encountered by the beveled edge of the descending front-plate and be forced backwardly into proper position.

The present improvements are illustrated in the accompanying drawings, in which—

Figure 1, is a vertical cross-section of the shuttle-box of the lay at the supply side of

the loom, showing the front-plate elevated into position for the insertion of a fresh shuttle. Fig. 2, is a similar cross-section showing the front-plate in its normal descended position.

A, is the lay; B, is the front-plate; C, is the binder constituting in this instance the rear of the shuttle-box and having the usual construction of a rear binder; D, is the top-plate of the shuttle-box; and E, is the race-plate. The front-plate is secured to a frame F, by means of arms G. This frame has hubs H, which slide on vertical rods I, fixed to brackets J, and K, fixed to the lay. The construction of this frame and guideway is similar to the construction set forth in the pending application of Edward S. Stimpson, filed March 8, 1906, Serial Number 304,852, excepting that in the present case the guideway for the frame compels the frame to move up and down at substantially right angles to the race-plate of the lay. The frame is lowered by means of springs L, (as in said Edward S. Stimpson application) and is elevated by any known means, such as the cam and intermediate instrumentalities shown in said application of said Edward S. Stimpson. As illustrated in the present drawings, a connecting link R, is pivoted to a stud S, on the frame F, which corresponds to the actuating link R, of said Edward S. Stimpson application.

The lower edge of the front-plate B, is thick as illustrated and it is beveled on its lower inner face as illustrated at T, in the drawings. The upper forward edge of the lay is recessed as shown at U, for the accommodation of the lower beveled edge of the front-plate. Consequently, as shown in Fig. 2, when the front-plate occupies its normal lowered position, the bevel T, is wholly below the top face of the race-plate so that the front-plate presents a continuous vertical face to bear against the front wall of the shuttle.

When the front-plate is elevated, as shown in Fig. 1, a fresh shuttle is inserted by a substantially horizontal rearward movement. The inserted shuttle (indicated at V) may occupy a misplaced position as indicated in Fig. 1. Nevertheless, the front-plate can descend because its bevel T, will encounter the upper forward edge of the shuttle and

force the shuttle back into proper position on the race-plate, ready to be picked truly through the shed. In case the binder is a forwardly spring-pressed binder (as is customary), and if the spring pressure is then on, the descending front-plate will force the shuttle back against the spring pressure.

Should the inserted shuttle be so badly placed that the front-plate cannot descend, no damage will ensue because the front-plate is pulled down by springs.

I claim—

1. An automatic shuttle-changing loom having, in combination, a movable front-plate for the shuttle-box at the supply side of the loom having a beveled inner edge adapted to move an inserted shuttle backwardly, and means for moving the front-plate.
2. An automatic shuttle-changing loom

having, in combination, a lay having a recess at its upper forward edge at the supply side of the loom, a guideway on the lay extending substantially at right angles to the race-plate of the lay, a frame sliding in said guideway, a front-plate for the shuttle box at the supply side of the loom carried by and moving with said frame, said front-plate having its lower edge beveled on its inner face, said bevel normally occupying the said recess in the lay, and means for raising and lowering said frame.

In witness whereof, I have hereunto signed my name in the presence of two subscribing witnesses.

WALLACE I. STIMPSON
